UNITED STATES PATENT OFFICE.

CURT HILSCHER, OF CHEMNITZ, GERMANY.

SHOCK ABSORBER FOR THE THREAD-GUIDE RAILS OF PARALLEL HOSIERY FRAMES.

Application filed August 26, 1921. Serial No. 495,810.

To all whom it may concern:

Be it known that I, CURT HILSCHER, a citizen of the German Republic, residing at Chemnitz, Germany, have invented certain new and useful Improvements in Shock Absorbers for the Thread-Guide Rails of Parallel Hosiery Frames, of which the following is a specification.

This invention relates to a parallel hosiery frame system "cotton". In frames of this type the rods on which the thread guides are arranged are arranged to reciprocate in longitudinal direction, a catch being provided for this purpose which is rigidly mounted 10 on a rod. This rod is drawn along by a friction element, the so-called brake, which is fixed on the rod supporting the thread guides, said rod serving as connecting member for the sinker inclines which produce the 15 movement of the sinkers.

The end movement of the rods which carry the thread guides is limited by adjustable abutments with which said rods come in contact. From the sudden interruption of 20 the movement of the rods, the jumping back of the same, and of the thread guides, interruptions of working of the frame occur.

This invention has for its object to do away with the above-mentioned inconvenience by retarding the movement of the rods for the thread guides shortly before the working travel comes to an end so that they move quite slowly against the corresponding abutment.

In order that the invention may be clearly understood, I shall proceed to describe the same with reference to the form of construction shown by way of example in the accompanying drawing, wherein:—

Fig. 1 shows in elevation one of the frame ends.

Fig. 2 is an end view of Fig. 1.

Figs. 3 to 8 illustrate the different working positions of the elements for producing the absorption of the shocks.

The thread-guide rails a are reciprocated in the well known manner by a bracket c , screwed upon the slur bar b which is moved to and fro in longitudinal direction according to the 50 sinker cam not shown in the drawing, drawing along a rod d with the aid of brake springs. At one end of this rod the driver for the thread-guide rails is arranged which consists of a guide piece e , f for a bolt g which 55 has a nose for gripping the required thread-

guide rail a to make the same participate in the reciprocating movement of the slur bar. The guide piece $e-f$, which is also called change-head, slides loosely upon a rod h and has a hub i with an inclined surface at 60 either side. The corresponding inclined surface of the hub i of the guide piece comes in contact with a correspondingly inclined end k' of a lever k (Figs. 1 and 6) shortly before the end of the path of the thread 65 guide (Fig. 4), said lever k being pivotally mounted upon the rod h and controlled by a pull spring l . The guide piece or change-head must now, in order to continue its travel, push the lever k aside by making the 70 same pivot around its rod h , the resistance regulated by the spring l producing thus the desired retardation of the speed of the change-head and consequently of the thread-guide rail until the rod d can slide in the 75 braking bracket e , wherefrom would result an idle course and the stopping of the change head i and of the thread-guide rail coupled with the same. At this moment a wedge 80 piece m fixed upon the slur bar gets under the pulley of the lever k (Figs. 5 and 6) so that this lever is lifted and the change-head i is released from the pressure exerted by 85 said lever. The braking bracket e can now bring the rod d and the change head with the thread-guide rail to the stops n or o which limit their stroke (Fig. 8) which is effected without shock as the parts to be moved cannot get the full speed owing to 90 the shortness of the travel.

When working in opposite direction the different parts work similarly, and the same elements for producing the absorption of the shock can be arranged in a similar manner at the other end of the frame.

This double arrangement of these elements can however be avoided if, as shown on Fig. 1, a second lever k^2 is arranged upon rod h with a hub having an inclined surface projecting in opposite direction to k' , said lever k^2 being connected by a rod p with the patented narrower (q , r) arranged at the other end of the knitting frame, not shown on the drawing.

I claim:—

A shock absorber for the thread-guide rails of parallel hosiery frames comprising in combination with the thread guide rails, with the driver for these rails, a hub of this driver having an inclined surface, a rod upon which 110

said driver is movably mounted and a slur bar, a spring influenced lever pivotally mounted upon said rod, a projecting hub of said lever having a contact surface inclined in opposition to the inclined surface of the hub of the driver, with which said driver comes in contact shortly before the end of its travel so that it has to overcome the resistance offered by this obstacle in order to retard the speed of said thread-

guide rails and a wedge piece on said slur bar for lifting said spring influenced lever.

In testimony, that I claim the foregoing as my invention, I have signed my name in presence of two subscribing witnesses.

CURT HILSCHER.
